Fig. 2

Fig. 3

Fig. 4

Fig. 1 is a front elevational view of a television cabinet, showing my new design;

Fig. 2 is a side elevational view as observed from the right thereof;

Fig. 3 is a fragmentary sectional view, drawn to an enlarged scale, and taken on line 3-3 of Fig. 1; and

Fig. 4 is also a fragmentary sectional view, drawn to an enlarged scale, the view being taken on line 4-4 of Fig. 1.

The dominant features of my design reside in those portions shown by full lines of the drawings.

I claim:

The ornamental design for a television cabinet, as shown and described.
